(57) **CLAIM**

The ornamental design for an electric scooter, as shown and described.

DESCRIPTION

FIG. 1 is a front, right, and top perspective view of an electric scooter, showing our design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a first angle of a connector.

FIG. 10 is a partial enlarged view of an area labeled 10 in FIG. 1 comprising a part of a first handle.

FIG. 11 is a partial enlarged view of an area labeled 11 in FIG. 2 comprising a part of a rear wheel.

FIG. 12 is a partial enlarged view of an area labeled 12 in FIG. 2 comprising a second angle of the connector; and, FIG. 13 is a partial enlarged view of an area labeled 13 in FIG. 3 comprising a part of a second handle.

The dash-dot broken lines are included to annotate partial views in FIGS. 1-3 & 9-13. All other broken lines represent portions of the article that form no part of the claimed design. None of the broken lines form a part of the claim.
